E. G. LINDHE

RADIATOR

Filed June 13, 1923

Inventor:
Eric G. Lindhe
by his attorney
Charles R. Scarle

UNITED STATES PATENT OFFICE.

ERIC G. LINDE, OF NEW YORK, N. Y.

RADIATOR.

Application filed June 13, 1923. Serial No. 645,050.

To all whom it may concern:

Be it known that I, ERIC G. LINDE, a citizen of the United States, residing in the city of New York, borough of Manhattan, in the county and State of New York, have invented a certain new and useful Improvement in Radiators, of which the following is a specification.

The invention relates to heat-exchange apparatus such as air cooled radiators for internal combustion engines, superheaters, condensers, steam heating radiators and the like, and the object of the invention is to provide a structure of this character which shall be light, easily and economically constructed and in which the interchange of heat shall be rapid.

A further object is to provide a structure for such service comprising a plurality of tubes, each adapted to offer greatly increased internal and external surface areas, and so formed as to cause the medium passing therethrough to make frequent changes in direction so that all portions of the medium are presented favorably to the tube wall.

Another important object is to arrange a group of such tubes in a radiator in such manner as to insure increased circulation of the external cooling medium and the presentation of the latter to all faces of each tube, whereby the efficiency of the radiator is increased.

The invention consists in certain novel features and details of construction and arrangement by which the above objects are attained, to be hereinafter described and claimed.

The accompanying drawings form a part of this specification and show an approved form of the invention as applied to the radiator of an automobile.

Figure 1 is a front elevation showing three adjacent tubes set in the plates of the upper and lower headers.

Figure 2 is a corresponding plan view showing a group of nine tubes.

Figure 3 is a horizontal section taken on the line 3—3 in Figure 1.

Figure 4 is a similar view taken on the line 4—4 in Figure 1.

Figure 5 is an elevation showing the same group of tubes seen angularly in the direction indicated by the arrow in Figure 2.

Figure 6 is an elevation of a tube-end on a larger scale, with a portion of the face

broken away sectionally to show the interior.

Similar reference numerals indicate the same parts in all the figures.

The tube is preferably formed by treating a length of seamless drawn cylindrical tubing, in suitable dies or otherwise, to produce a succession of cells connected by flattened necks or throats, the plane of each throat lying at a right angle to the next, with the ends of the tube left in the original cylindrical form for easy attachment to the header plates or other connection.

The lower plate of the upper header and upper plate of the lower header are marked 10 and 11 respectively and receive the ends 12 of a group of tubes and which may be understood to be soldered therein. The crimping or compressing process by which the cells are formed shortens the tube, and as the metal is merely forced inwardly from opposite sides the walls are not drawn or strained and their strength is not impaired.

The cells are marked 13, and the constricted flattened throats 14, and, as shown in Figures 3 and 4, the alternate flattening or crimping in opposite directions to form the cells and throats changes the tube from the cylindrical to a rectangular form in plan, having four faces each approximating the appearance shown in Figure 1, and when viewed corner-wise appears as illustrated in Figure 5.

In grouping the tubes for service as an air-cooled radiator for cooling the circulating water of an automobile motor, the tubes are preferably arranged vertically in closely spaced parallel rows, as shown, with their faces in the same vertical planes and with each series of throats 14 having the same inclination lying in the same horizontal plane and at a right angle to the next succeeding series, thus producing a plurality of laterally extending diagonal air passages or channels 15 traversing the group alternately in opposite directions. The current of air induced by the usual fan, not shown, is diverted angularly to the right and left by these channels and all parts of the external surfaces of the tubes are bathed in the current by reason of the eddies and counter-currents thus induced; there are no "dead" spaces or pockets.

The water traversing the interior of the tube changes its direction angularly in each

passage from one cell to the next and is also given a spiral movement, the combined effect being to present positively all parts of the water column successively to the walls of the tube. While there is no uninterrupted channel for an idle flow of water from one header to the other, the changes in direction are not abrupt, the transition being easily and smoothly effected by the curved walls of the throats and cells.

By the above described distribution and baffling of the air and water currents the desired interchange of heat units is efficiently attained.

Although the invention is shown and described as applied to the radiator of an internal combustion engine, it will be understood that the heat-exchange cellular tubes may be employed in steam heating radiators and in condensers, superheaters, refrigerating apparatus, and in other heat-exchange situations to which they may be adapted.

The cylindrical tube-end in Figure 6 is shown screwthreaded to receive a return-bend or other connection for house heating.

In radiators or condensers for cooling liquids the cell-shaped tube affords a marked efficiency by the upsetting of the liquid column in the successive steps throughout the entire length of each tube unit. In an assembly of a plurality of tubes the louver principle employed tends to produce eddy currents in either the air or liquid circulating as the cooling agent, thereby effecting greater outer surface contact than normally would obtain in the use of cylindrical or

other tubes of regular form. These features are utilized to advantage in condensers or superheaters as well as in radiators.

I claim:—

1. A radiator composed of a plurality of tubes each comprised of a series of cells connected by flattened throats, each alternate throat at an angle to the next, and arranged in a group with the throats of the same angularity lying in the same planes, to produce a plurality of series of channels between adjacent throats extending diagonally through such group. 40 45

2. A radiator composed of a plurality of vertical tubes each comprising a series of cells connected by flattened throats, each alternate throat being at an angle to the next, said tubes arranged in rows with said throats extending diagonally to the vertical 50 55 planes of such rows.

3. A radiator composed of a plurality of tubes each formed of a series of cells connected by flattened throats, each alternate throat at a right angle to the next, said tubes arranged one behind the other in straight rows in parallel vertical planes in both directions, with the throats of the same angularity lying in the same horizontal plane and at an angle to said vertical 60 65 planes, to present a plurality of series of horizontal channels extending diagonally through such rows, each series of channels crossing the next succeeding series.

In testimony that I claim the invention above set forth, I affix my signature hereto.

ERIC G. LINDHE.
